MAST CLIMBING DEVICE OR SIMILAR ARTICLE

William J. Price, 3823 E. Lake Way, Redwood City, Calif.
94062; Richard W. Cooper, 1000 Ignacio Blvd., Apt. 51,
Novato, Calif. 94947; and Robert A. Gates, 4018
Bennett Valley Road, Santa Rosa, Calif. 95403

Filed Apr. 7, 1971, Ser. No. 132,266

Term of patent 7 years

Int. Cl. D2—04

U.S. Cl. D2—317

FIG. 1

FIG. 3

FIG. 2

FIG. 4

FIG. 5

FIG. 6

FIG. 7

FIG. 1 is a top perspective view of a mast climbing device showing our new design;

FIG. 2 is a top plan view thereof;

FIG. 3 is a front elevational view;

FIG. 4 is a side elevational view taken from the right of FIG. 1;

FIG. 5 is a rear elevational view;

FIG. 6 is a side elevational view taken from the left of FIG. 1; and

FIG. 7 is a bottom plan view.

We claim:

The ornamental design for a mast climbing device or similar article, as shown.
